UNITED STATES PATENT OFFICE.

KURT BÖHME, OF BERLIN-SIEMENSSTADT, GERMANY, AND KARL GIESE, OF NOWAWES, NEAR GERMANY, ASSIGNORS TO SIEMENS & HALSKE AKTIENGESELLSCHAFT WERNERWERK, OF SIEMENSSTADT BEI BERLIN, GERMANY.

BANK CONTACT FOR TELEPHONE SWITCHES.

Application filed November 25, 1922, Serial No. 603,170, and in Germany March 12, 1921.

This invention relates to the bank contacts of switches used in telephone systems more particularly to those made up of separate strips in switches having the contact strips 5 located at right angles to the direction of rotation of the switch wipers.

The object of the invention is to facilitate the process of assembling and dismounting the bank contacts at the switch racks, and 10 more particularly to enable the individual strips of contacts to be easily replaced without disturbing the operation. The invention furthermore enables several switches to be compactly located above one another.

15 According to the invention a contact bank is formed of contact strips that are connected with the switch rack by fastening means provided partly at the switch rack and partly at the contact strips. The strips forming 20 the contact bank are preferably connected to the switch rack by means of a fastening, which can be closed by pushing one part into the other in a radial or oblique direction with respect to the switch shaft. The strips of 25 bank contacts can be secured in place by a fastening which embraces these strips at their end surfaces located parallel to the switch shaft. The fastening can comprise a band provided at intervals with fixing 30 means that engage corresponding means in the strips of bank contacts. The fixing means provided at each strip of bank contacts are preferably interconnected by a metal plate, which also acts as a stiffening 35 piece.

According to the invention the switch rack can be provided with cylindrically shaped holding members having slots, into which fits sideways extension pieces at the upper and 40 lower ends of the contact strips. The slots engaged by one end of the contact strips are of sufficient length to allow the ends of the contact strips to move freely therein in a longitudinal direction.

45 The drawing shows one method of carrying out the invention.

Figure 1 shows an elevation and Figure 2 a plan view of the contact bank. Figure 3 shows a side elevation and Figure 4 a plan 50 view of a single contact strip.

The switch rack is composed of upright rails *a* and interconnecting pieces *b*. The latter take the form of a segment and their

curved parts are provided with flanges *c*, *c'* extending upwards and downwards. These 55 flanges are at regular intervals provided with vertical slots *d*, *d'*, into which fit the tongues *e*, *e'* of the contact strips *f*. These tongues and slots are so shaped in the example illustrated, that they can be pushed into one another in a direction, which is radial with respect to the switch shaft. They could however be so shaped that they can be pushed into one another obliquely to the switch 60 shaft.

It will be seen from Figure 2 that the contact strips *f*, are mounted fanwise at regular intervals to the flanges *c*, *c'* by inserting the tongues *e*, *e'* into the slots *d*, *d'*. Each contact strip *f* comprises a row of contacts *g*, around which is pressed rectangularly shaped insulating material through which the ends of the contacts extend at both sides. The two tongues *e*, *e'* projecting at top and bottom of the strips comprise the legs of a U shaped plate *h* which is covered with the insulating material. This plate extends through holes *o* (Figure 4) in the contacts *g* and serves to stiffen the contact strip *f*. The metal plate *h* also serves as an earth plate 70 for conducting away currents which might occasion cross talk.

In order to enable the strip *f* to be easily replaced the slots *d'* of one of the flanges *c'* are made long enough to allow the corresponding tongues *e'* to have sufficient play in the longitudinal direction. Each contact strip *f* has a notch *i* at its outer end surface which is parallel to the selector shaft. A metal band *m* fastened to the selector frame 85 has projections *k* at regular intervals. When a strip *f* is mounted on the switch rack, its notch *i* engages a projection *k*. This ensures that the strips retain their correct fan shaped location on the rack. Alternately the strips *f* could be provided with pins to engage corresponding holes in the metal band *m*.

The metal band *m* is adapted to be easily removed from the rack. For this purpose it is provided with slots, which engage with rivets or pins *q* on flanges *r* on the rack. After the band *m* has been removed, it is therefore, possible to quickly remove and replace the individual contact strips *f* as required without having to loosen a screw. The band *m* could, however, be secured to

the rack by means of screws or in any other manner desired.

What we claim and desire to protect by Letters Patent is:—

- 5 1. The combination, in a contact bank for a telephone switch, of a pre-assembled switch rack, a plurality of separate contact strips, and means for mounting said contact strips on upper and lower portions of said pre-assembled switch rack to form a complete contact bank, while maintaining the upper and lower portions of the rack intact, and a single element for holding all the contact strips in place on said rack.
- 15 2. The combination, in a contact bank for a telephone switch, of a pre-assembled switch rack having two horizontal members, a plurality of flat contact strips, and means including the horizontal members of the switch rack and a band secured at two points to said rack and encircling said contact strips for supporting said strips side-wise in fixed relation to said switch rack.
- 25 3. The combination, in a contact bank for a telephone switch, of two substantially parallel curved supporting members having perforations therein, a plurality of separate contact strips each having two lugs, the lugs of each strip adapted to enter radially perforations in the curved members, respectively, notches in the outer edges of said contact strips, an encircling band secured to the switch rack at two points and passing around the outside edges of all the contact strips, and notches in said band cooperating with the notches in the outside edges of said strips to hold said contact strips in fixed space relation to each other.
- 35 4. The combination, in a contact bank for a telephone switch, of a support, having a pair of horizontal bars in permanent fixed relation to each other, a plurality of flat contact strips mounted on the bars of said support while maintaining the bars intact, and means on the bars of said support and on said strips including lugs in one case and cooperating mortises in the other case for substantially preventing sidewise and endwise movement of said contact strips with respect to the support.
- 45 5. The combination, of a pre-assembled semi-circular telephone switch rack, and a plurality of vertically arranged separate contact strips each comprising a plurality of contacts and adapted to be moved in a radial direction into position on said switch rack to form a complete contact bank.
- 55 6. A bank contact assembly comprising a plurality of perforated individual contacts arranged in a row one above the other and embedded in insulating material, and a metallic stiffening members passing through the perforations in the contacts.
- 65 7. The combination, in a contact bank for a telephone switch, of a support, a plurality

of flat contact strips mounted on said supports, means on said support and on said strips including lugs in one case and cooperating mortises in the other case for substantially preventing side-wise and endwise movement of said contact strips with respect to the support, and a semi-circular band secured at either end passing around the outer edges of the contact strips to maintain them tight up against the support.

8. The combination, in a contact bank for a telephone switch, of a support, a plurality of flat contact strips mounted on said support, means on said support and on said strips including lugs in one case and cooperating mortises in the other case for substantially preventing side-wise and endwise movement of said contact strips with respect to the support, and a semi-circular band secured at either end passing around the outer edges of the contact strips to maintain them in fixed space relation to each other.

9. The combination, in a contact bank for a telephone switch, of a support, a plurality of flat contact strips mounted on said support, means on said support and on said strips including lugs in one case and cooperating mortises in the other case for substantially preventing side-wise and endwise movement of said contact strips with respect to the support, and a semi-circular band secured at either end passing around the outer edges of the contact strips to maintain them tight up against the support and to maintain them in fixed space relation to each other.

10. A bank contact assembly comprising a plurality of individual contacts arranged in a row one above the other and embedded in insulating material, and a metallic member embedded in said material in a right angle to said contacts and provided with lugs extending from the member in a right angle in a plane parallel to the contact elements.

11. In an automatic switch structure, a support, banks of contacts having lugs entering openings in said support, and means located back of said contact banks and midway between the upper and lower ends thereof for firmly holding said banks in fixed relation to said support.

12. A contact assembly comprising a plurality of individual contacts arranged one above the other and embedded in a block of insulating material, the ends of said contacts projecting through opposite surfaces of said block, and two mechanically inter-connected lugs also embedded in said block and projecting through one surface through which said contacts project, one lug projecting above the contacts, the other lug projecting beneath the contacts.

13. A bank contact assembly comprising a plurality of perforated individual contacts

arranged in a row one above the other, a
metallic stiffening member passing through
the perforations in said contacts, projecting
lugs on said member, one at either end of
said assembly, said contacts, member and
projecting lugs all embedded in insulating
material.
